FOREIGN PATENT DOCUMENTS

EP 1617015 B1 9/2009

Primary Examiner — Samantha Q Lawrence(74) *Attorney, Agent, or Firm* — Reinhart Boerner Van Deuren s.c.(57) **CLAIM**

I claim the ornamental design for the mast base connector, as shown and described.

DESCRIPTION

FIG. 1 is a top front perspective view of a mast base connector;

FIG. 2 is a top rear perspective view thereof;

FIG. 3 is a bottom rear perspective view thereof;

FIG. 4 is a bottom front perspective view thereof;

FIG. 5 is a front view thereof;

FIG. 6 is a rear view thereof;

FIG. 7 is a right side view thereof;

FIG. 8 is a left side view thereof;

FIG. 9 is a top view thereof;

FIG. 10 is a bottom view thereof; and,

FIG. 11 is a top front perspective view thereof.

1 Claim, 11 Drawing Sheets(56)
